UNITED STATES PATENT OFFICE.

CHARLES E. HART, OF NEW BRITAIN, CONNECTICUT, ASSIGNOR TO THE
STANLEY WORKS, OF SAME PLACE.

INSIDE-CORNER IRON.

SPECIFICATION forming part of Letters Patent No. 471,610, dated March 29, 1892.

Application filed December 16, 1891. Serial No. 415,232. (No model.)

To all whom it may concern:

Be it known that I, CHARLES E. HART, a citizen of the United States, residing at New Britain, in the county of Hartford and State 5 of Connecticut, have invented certain new and useful Improvements in Inside-Corner Irons, of which the following is a specification.

My invention relates to improvements in corner irons or braces for use upon the inside 10 corners of post-office boxes and other articles; and the object of my improvement is to produce such an iron at a small cost and of superior utility.

In the accompanying drawings, Figure 1 is 15 a front elevation of my corner-iron; and Fig. 2 is a side elevation of the same, together with a sectional view of one corner of a box to which said iron is applied.

I make my corner-iron of sheet-metal cut 20 to proper form, and perforated, as may be desired, for the insertion of screws or nails in securing the iron in place. It is bent up to form two wings A, which stand at right angles to each other, with an inclined brace-like portion 25 3 between them, forming a truncated angle at their junction, as shown. The whole is further strengthened and given a neater appearance by the two beads 4, swaged or struck up near the side edges and extending over a 30 portion of one wing across the brace-like portion and over a portion of the other wing, said beads being struck from the back or out-

side of said iron so as to project on their inner face, as shown.

In use the iron is secured to the inside corner of the box or receptacle B or in the corner of any base and upright portion, to not only hold the adjacent sides thereof firmly together, but to form a short brace in the corner to prevent the box from racking. The 35 40 brace-like portion, besides giving increased strength, enables the wings of the iron to set close against the sides of the box, even if the corner is partly filled up with trimmings or other matter.

45 I claim as my invention—

1. The inside-corner iron herein described, consisting of the two wings for securing the article in place, and the inclined brace-like portion at the corner between said wings, 50 substantially as described, and for the purpose specified.

2. The inside-corner iron herein described, consisting of the two wings, the inclined brace-like portion at the corner between said wings, 55 and the beads 4, projecting from the inside of said wings and extending over said brace-like portion, substantially as described, and for the purpose specified.

CHARLES E. HART.
